UNITED STATES PATENT OFFICE.

RALPH G. WHITLOCK, OF LOS ANGELES, CALIFORNIA.

BACK-FRAME FOR LOOSE-LEAF BOOKS.

1,241,692.

Specification of Letters Patent.

Patented Oct. 2, 1917.

Application filed October 16, 1916. Serial No. 126,045.

To all whom it may concern:

Be it known that I, RALPH G. WHITLOCK, a citizen of the United States, residing at the city of Los Angeles, in the county of Los Angeles and State of California, have invented new and useful Improvements in Back-Frames for Loose-Leaf Books, of which the following is a specification.

My invention relates to improvements in the construction of the back frame for loose leaf books out of sheet metal and the object thereof is to simplify and cheapen the construction of said back frames and at the same time to provide a simpler and more efficient frame than is now in common use.

In the drawings forming a part of this application:

Figure 1 is a side elevation of a completed back frame.

Fig. 2 is a top plan of the frame shown in Fig. 1.

Fig. 3 is an enlarged elevation of the control end of the frame with the leaf holding rings closed.

Fig. 4 is an enlarged section on the line 4-4 Fig. 2, with the rings in open position.

Fig. 5 is an enlarged section on the line 5-5 of Fig. 2, of so much of the frame as shows the connection between the body members.

Fig. 6 is a plan of a sheet metal blank partly broken from which the body members, ring members and connecting members are formed.

Referring to the drawings the body members 10 are formed of that portion of the blank between the dotted lines 11-11 of Fig. 6, which is pressed or formed into round rods.

The ring members 12 are formed of those portions of the blank extending above the dotted lines 13.

The hinge members 14 at the ends are formed of those portions outside the dotted lines 11, and the intermediate hinge members 15 are formed of those portions below the dotted lines 16. Those portions below dotted lines 17 form what is termed brace members 18. By subjecting the blank shown in Fig. 6 to successive bending operations the hinge members and ring members and side members and brace members for one

half of the back frame are produced. The other half is a duplicate of the one described. Those portions intended for hinge members are perforated by perforations marked 19 to receive the pintle rod 20, which is passed through them when the parts are assembled. The brace members are bent over and pressed into the grooves in the back of the ring members, thereby stiffening and bracing the ring members.

A coil spring 21 is wound around rod 20 near hinge members 15 and has its free ends bearing against the side members to close the ring members after they are opened and released as hereafter explained. Secured upon rod 20 near one of the ends thereof is a fulcrum bar 22 on which bar is pivotally mounted an L-shaped lever by means of which the body members of the back frame are caused to approach each other, thereby opening the ring members. This lever may be termed an opening lever and is composed of the shanks 23 which are pivotally mounted on the ends of the fulcrum bar, and the body members 24 which lie at right angles to the shanks. The shanks are separated and a portion of the body member is cut away to permit it to pass over the end of rod 20 when the ring members are being opened. Secured to shanks 23 is a locking lug 25 which passes between the hinge members 14 at that end of the frame and is received in notches 26 when the ring members are in their closed position. This locking lug could be formed integral with the lever.

When the ring members are in their closed position shanks 23 lie in a plane parallel with the plane of the body members of the back frame as shown in Figs. 1 and 3. By pressing on the top of the opening lever its shanks press against the body members of the back frame and force them toward each other, thereby opening the ring members and locking them open. When the opening lever is returned to its normal position which is the position shown in Fig. 1, spring 21 returns the other parts of the frame to their normal positions. The back frame is suitably attached to the cover not shown in the well known manner. By this construction it will be seen that I have provided a back frame for loose leaf books which is

simple in operation and economical to manufacture.

Having described my invention what I claim is:

5 1. A back frame for loose leaf books in which the ring members, the hinge members and body members, and brace members are formed from blanks stamped from sheet metal, said ring and brace members being on opposite edges of the body members when first stamped; said brace members being adapted to be bent and pressed into the grooves in the backs of the ring members, the different parts of the blank being 10 pressed into appropriate shape, the same shaped blank being used for either side.

2. A back frame for loose leaf books in which the ring members, the hinge members and body members, and brace members are 20 formed from blanks stamped from sheet metal; said ring and brace members being on opposite edges of the body members when first stamped, said brace members being adapted to be bent and pressed into the 25 grooves in the backs of the ring members, the different parts of the blank being pressed into appropriate shape, the same shaped blank being used for either side; and a pintle rod connecting the parts of one side 30 of the back frame with those of the other side.

3. A back frame for loose leaf books in which the ring members, the hinge members and body members, and brace members 35 are formed from blanks stamped from sheet metal; said ring and brace members being on opposite edges of the body members when first stamped, said brace members being adapted to be bent and pressed into the 40 grooves in the backs of the ring members, the different parts of the blank being pressed into appropriate shape, the same shaped blank being used for either side; and a pintle rod connecting the parts of one 45 side of the back frame with those of the other side; and a spring coiled on said pintle rod and having its free ends bearing against the body members to close and hold the ring members closed.

50 4. A back frame for loose leaf books in which the ring members, the hinge members and body members, and brace members are formed from blanks stamped from sheet metal, said ring and brace members being 55 on opposite edges of the body members when first stamped, said brace members being adapted to be bent and pressed into the grooves in the backs of the ring members, the different parts of the blank being 60 pressed into appropriate shape, the same shaped blank being used for either side; and a pintle rod connecting the parts of one side of the back frame with those of the other side; and a spring coiled on said pintle rod 65 and having its free ends bearing against the

body members to close and hold the ring members closed; and an opening lever operatively connected to said pintle rod adapted to open and hold open the ring members and to hold the ring members locked when in 70 their closed position.

5. A blank for back frames for loose leaf books comprising a longitudinal body member; hinge members projecting from the body member at the ends and from one side 75 thereof; ring members projecting from the side of the body member, all of said members stamped from sheet metal and adapted to be bent into suitable shape and being integral.

6. In a back frame for loose leaf books 80 longitudinal body members, ring members secured to said body members and adapted to be bent into shape, brace members secured to said body members adapted to be pressed to form supports for the ring members, 85 hinge members secured to the body members adapted to be bent into shape, all of said members being stamped from sheet metal and being integral and a pintle bolt uniting said hinge members.

7. In a skeleton back frame for loose leaf books blanked from sheet metal, side members formed into circular tubes; and ring members, each formed with a trough in its outer surface, said members being integral. 90

8. In a skeleton back frame for loose leaf books blanked from sheet metal, side members formed into circular tubes; ring members projecting from the inner edges of the side members and formed with troughs in 100 their outer surfaces; brace members projecting from the edges of the side members opposite the ring members and adapted to be wedged in the troughs of the ring members; hinge members connected to the side members intermediate their ends; and a pintle rod connecting said hinge members. 105

9. A skeleton back frame for loose leaf books comprising side members having ends bent for hinged connection; ring and brace 110 members projecting from opposite edges of the side members; hinge members projecting from the side members intermediate their ends, all of said members being integral; and a pintle bolt connecting said hinge members. 115

10. In a skeleton back frame for loose leaf books of the character described, an L-shaped opening lever having shanks adapted to be hingedly connected to the pintle rod and a cut-out body at right angles to the 120 shanks, said shanks being adapted to lie on and parallel with the side members when in their inoperative position, and to depress and hold the side members at a greater distance from the pintle rod when in their operative position than the normal position of said side members, for the uses as herein described.

11. In a skeleton back frame for loose leaf books of the character described, the combi- 130

nation of side members hingedly connected by a pintle rod; with an L-shaped operating lever consisting of shanks and a cutout body at right angles to the shanks, said shanks being hingedly connected to the pintle rod; and a lug secured to said shanks adapted to lie between the ends of the side members

when the parts are in their closed position and lock them from opening accidentally.

In witness that I claim the foregoing I ¹⁰ have hereunto subscribed my name this 9th day of October, 1916.

RALPH G. WHITLOCK.
